DESIGN FOR A FOLDING FOLIO FOR PHOTOGRAPHIC PRINTS

Clark H. Geppert, Des Moines, Iowa

Application May 24, 1940, Serial No. 92,560

Term of patent 7 years

To all whom it may concern:

Be it known that I, Clark R. Geppert, a citizen of the United States and a resident of Des Moines, in the county of Polk and State of Iowa, have invented a new, original, and ornamental Design for a Folding Folio for Photographic Prints, of which the following is a specification, reference being had to the accompanying drawing, forming part thereof, in which:

Fig. 1 is a perspective view of a folding folio

for photographic prints, in a partially opened position, showing my new design; and

Fig. 2 is a fragmentary enlarged view for the purpose of showing more clearly the details of ornamentation.

I claim:

The ornamental design for a folding folio for photographic prints, as shown and described.

CLARK H. GEPPERT.
